UNITED STATES PATENT OFFICE.

CHARLES MILES COX, OF STRAIGHT, PENNSYLVANIA.

BRACKET.

1,409,525.

Specification of Letters Patent. Patented Mar. 14, 1922.

Application filed July 13, 1921. Serial No. 434,452.

To all whom it may concern:

Be it known that I, CHARLES M. COX, a subject of the King of Great Britain, and a resident of Straight, in the county of Elk 5 and State of Pennsylvania, have invented certain new and useful Improvements in Brackets, of which the following is a specification.

This invention relates to brackets especially adapted for supporting mirrors.

An important object is to provide a bracket capable of a variety of adjustments so that the mirror supported thereby may be conveniently positioned with relation to 15 light and with relation to the user of the mirror.

Further, the invention aims to provide a bracket of the class described which may be conveniently applied to the wall without 20 mutilating or in any way marring the appearance of the wall.

A still further object is to provide a bracket of the class described which is neat in appearance, durable in use, and cheap to 25 manufacture.

Other objects and advantages of the invention will be apparent during the course of the following description.

In the accompanying drawing:—

30 Figure 1 is a plan view of the bracket applied.

Figure 2 is a side elevation of the same applied.

In the drawing the numeral 5 designates 35 a wall to which the improved bracket generally designated by the numeral 6 is applied. As illustrated in Figure 2 upper and lower L-shaped brackets or attaching members are applied to the wall and consist of 40 base plates 8 and outwardly projecting apertured ears 9. The aperture in the lower ear 9 is smaller than the diameter of a vertically arranged rod 10 having its lower end mounted on the lower ear 9 and secured 45 thereto by a thumb screw 11. The thumb screw 11 is provided with a threaded shank freely passed through the aperture in the lower ear and threaded into an axial opening in the lower portion of the rod 10. By 50 tightening up on the thumb screw 11 the rod 10 is securely held in position and when it is desired to remove the rod it is merely necessary to detach the thumb screw 11 and subsequently move the rod 10 upwardly 55 through the upper ear 9.

The arm of the bracket consists of co-act-

ing sections 14 and 15 having their adjacent end portions formed with overlapping ears 16 which receive a fastening screw 17. The head of the fastening screw 17 is countersunk in the lower ear 16 and the shank of the screw is threaded into the upper ear whereby to adjustably connect the sections 14 and 15. By loosening the fastening screw 17 slightly the sections 14 and 15 may be 60 adjusted about the vertical axis of the fastening screw.

As illustrated in Figure 2 the rear portion of the section 14 is gradually enlarged and is formed with a vertical bearing sleeve 70 18 which receives the rod 10 and is adjustable thereon. The sleeve 18 may be held in an adjusted position on the rod 10 by means of a set screw 20 threaded through the sleeve and engaged with the rod. The sleeve 18 is 75 not only capable of vertical adjustment on the rod 10 but may also be adjusted so as to position the section 14 either to the right or to the left.

A head is mounted upon the outer end of 80 the section 15 and includes an attaching ear 22 secured to the section by means of a fastening screw 24 similar in construction to the fastening screw 17. The aforesaid head also comprises a transversely extending 85 bearing sleeve 24' having its under side flush with the base plate or ear 22 and its upper side extended above the base plate. The transversely extending sleeve 24' slidably receives a cylindrical rod 26 which is engaged 90 by a thumb screw 28 threaded through one side of the sleeve for holding the rod in an adjusted position.

The mirror 30 is secured to a pair of mirror attaching plates 31 having their rear 95 portions formed with ears 33 adjustable on the rod 26 and secured thereto by means of thumb screws 34.

In operation the mirror may be adjusted 100 about the axis of the rod 26 so that the same will be properly inclined and when desired the head may be adjusted about the axis of the fastening screw 24. Also, the sections 14 and 15 are capable of adjustment about the longitudinal axis of the fastening screw 17. The improved bracket may be further 105 adjusted either vertically or about the longitudinal axis of the rod 10. It is therefore apparent that by reason of the multiplicity of adjustments the mirror may be positioned 110 properly with respect to the light and with respect to the person using the mirror.

I claim:—

A mirror supporting bracket comprising a pair of attaching plates having means whereby the same may be secured to a mirror, said attaching plates also being provided with apertured ears, a horizontally arranged rod having its end portions extending through said ears, a head having a tubular portion receiving said horizontally arranged rod and arranged between said attaching plates, an arm inclusive of a pair of adjustably connected sections, one of which

is provided with a sleeve and the other being adjustably connected to said head, whereby the head may be adjusted about a vertical axis, a second rod arranged vertically and extended through said sleeve, a set screw carried by said sleeve and engaging said rod, attaching devices for securing said second named rod to a support, and set screws connecting said attaching plates to said first named rod whereby to hold the mirror in an inclined or vertical position.

CHARLES MILES COX.
